(57) **CLAIM**

I claim the ornamental design for an easel, as shown and described.

DESCRIPTION

FIG. 1 is a front perspective view of a first preferred easel shown in a folded closed configuration.

FIG. 2 is a back perspective of the easel of FIG. 1.

FIG. 3 is a top view of the easel of FIG. 1.

FIG. 4 is a bottom view of the easel of FIG. 1.

FIG. 5 is a front view of the easel of FIG. 1.

FIG. 6 is a back view of the easel of FIG. 1.

FIG. 7 is a first side view of the easel of FIG. 1.

FIG. 8 is a second side view of the easel of FIG. 1.

FIG. 9 is a front perspective view of the first preferred easel in a first open configuration with the brush box substantially parallel to the painting (central) and the palette (distal) compartments.

FIG. 10 is a back perspective of the easel of FIG. 9.

FIG. 11 is a top view of the easel of FIG. 9.

FIG. 12 is a bottom view of the easel of FIG. 9.

FIG. 13 is a front view of the easel of FIG. 9.

FIG. 14 is a back view of the easel of FIG. 9.

FIG. 15 is a first side view of the easel of FIG. 9.

FIG. 16 is a second side view of the easel of FIG. 9.

FIG. 17 is a front perspective view of the first preferred easel in a second open configuration with an inner cover of the palette (distal) compartment open and the brush box partially open.

FIG. 18 is a back perspective of the easel of FIG. 17.

FIG. 19 is a top view of the easel of FIG. 17.

FIG. 20 is a bottom view of the easel of FIG. 17.

FIG. 21 is a front view of the easel of FIG. 17.

FIG. 22 is a back view of the easel of FIG. 17.

FIG. 23 is a first side view of the easel of FIG. 17.

FIG. 24 is a second side view of the easel of FIG. 17.

FIG. 25 is a front perspective view of the first preferred easel in a third open configuration with an inner cover of the palette (distal) compartment wrapped over the back of the palette (distal) compartment and with the brush box open.

(Continued)

FIG. 26 is a back perspective of the easel of FIG. 25.
 FIG. 27 is a top view of the easel of FIG. 25.
 FIG. 28 is a bottom view of the easel of FIG. 25.
 FIG. 29 is a front view of the easel of FIG. 25.
 FIG. 30 is a back view of the easel of FIG. 25.
 FIG. 31 is a first side view of the easel of FIG. 25; and,
 FIG. 32 is a second side view of the easel of FIG. 25.
 The broken line depictions in the figures are included for environmental purposes and form no part of the claimed design.

1 Claim, 22 Drawing Sheets
